MAGAZINE SAFETY RAZOR

Edward F. Bleeker and Peter J. Ditto,
Plattsburg, N. Y.

Application August 6, 1948, Serial No. 42,806

3 Claims. (Cl. 30—40)

1

This invention relates to an improved magazine safety razor.

An object of the invention is the provision of a safety razor in which a head has a repository for used blades and a magazine for supplying fresh blades with a top plate slidable over the upper open ends of the repository magazine and the usual guard for moving a used blade into the repository while shifting a fresh blade into an operative shaving position on the guard.

A further object of the invention is the provision of a safety razor in which a head has a repository for used blades and a magazine for furnishing fresh blades, a slidable means on the head being shiftable in one direction for withdrawing a used blade to a position over the repository when spring fingers on the head release said blade for discharge into the repository, the slidable means when moved in the opposite direction, shifting a new blade projected from the magazine into shaving position over a guard at one end of the head.

The invention is best understood from a consideration of the following detailed description in connection with the accompanying drawings, nevertheless it is to be understood that the invention is not confined to the disclosure but is susceptible of such changes and modifications as shall define no material departure from the salient features of the invention as expressed in the appended claims.

In the drawings:

Figure 1 is a side view in elevation of our combined magazine and safety razor.

Figure 2 is a plan view of the razor.

Figure 3 is a transverse vertical section of the safety razor head showing a chamber for used blades and a magazine for new blades.

Figure 4 is a transverse vertical section similar to that shown in Figure 3 with a top plate withdrawn to the rear end of the head.

Figure 5 is a transverse vertical section taken along the line 5—5 of Figure 3.

Figure 6 is a rear end view of the razor looking in the direction of the arrows in Figure 1.

Figure 7 is a front end view of the razor as indicated by the arrows in Figure 1.

Figure 8 is a transverse vertical section taken along the line 8—8 of Figure 3.

Figure 9 is a top plan view of the head with the slidable top plate removed.

2

Figure 10 is a horizontal section taken along the line 10—10 of Figure 9.

Figure 11 is a bottom plan view of the sliding top plate, and

Figure 12 is a longitudinal vertical section taken along the line 12—12 of Figure 2.

Referring more particularly to the drawings 10 designates generally a head of a safety razor comprising a main body portion 11 from which projects a guard 12 and a slidable top plate 13. A handle 14 has a cup-shaped member 15 adapted to receive a ball 16 at the free end of a stem 17 projecting downwardly from the under face of the body 11.

The body has a chamber or repository 20 for used blades 21. Said chamber is located at the front of the body and at the rear of the guard 12 (Figs. 3 and 4). The bottom of said chamber is open but is closed normally by a slide 22 guided in parallel tracks 23 and 24 at the lower edges of the side walls of the chamber. A finger piece 25 on the outer end of said slide is employed for shifting the slide to remove used blades from the chamber 20. Spring fingers 26 are secured at 27 to the top of a partition 28 between the chamber 20 and a chamber 29 for fresh blades 30. The free ends of the spring fingers being curved are seated at the inner ends of slots 31 in the top plate 13 and above the top surface of a blade 30 which is in an operative shaving position on the guard 12 (Fig. 3). These fingers act as guides when the plate 13 is drawn rearwardly for directing said blade, when dull, into the chamber 20. Lips 32 at the front of the guard retain the blade against outward movement.

Each blade 30 as shown in Figure 9 has a beveled front cutting edge 35 and a rear straight edge 36 thereby providing blade with a single cutting edge. Spaced openings 37 are formed in the blade to receive pins 38 projecting downwardly from the underface of the top plate so that when said plate is shifted in either direction the blades will be shifted likewise.

The chamber 29 forming a magazine has an elongated opening in the bottom which is closed by a slide 40 mounted in guides 41 and operated by a finger piece 42. A flat spring 43 has one end welded or riveted to the upper surface of a plate 43a loose on said slide while the free end thereof presses against the blades 30 in the magazine for

45

retaining said blades against the inner face of the top plate 13 and for seating the uppermost blade in a cut-out portion 44 at the inner face of the top plate adjacent the front edge thereof. It will be noted from Figures 3 and 4 that the inner surface 45 of the cut-out portion 44 is located in a horizontal plane and above the bottom face of the plate 13. The inner surface of the top plate is further cut-away at 46 to form an inclined inner surface cooperating with the surface 44 to 10 provide a shoulder 47 for engagement with the rear edge of the blade 30.

The top plate 13 (Fig. 5) has inwardly curved flanges 50 along the end edges to receive semi-circular ribs 51 on the end walls of the body 11 for slidably mounting said plate. A pin 52 projecting upwardly from the rear wall 53 of the body 11 has its free end riding in a groove 54 (Fig. 11) formed at the inner face of the plate 13. The shoulders 55 and 56 at the ends of the groove act as stops when the plate is shifted in opposite directions.

When the top plate is shifted to the position shown in Figure 3, it is locked in place by a latch 57 (Fig. 2) pivoted at 58 on the side walls of a slot 59 formed in one end of the plate. One free end of said latch engages a recess 60 in an end wall of the body 11. A coil spring 61 engaged between a button 62 on the other end of the latch and a flange 63 on the top plate 13 maintains the latch in the recess 60 and the button 62 projected outwardly from the end wall of the top plate in order that said button may be depressed readily to release said plate for sliding movement on the body 11.

The handle 14 (Fig. 1) has a central longitudinal passage 65 to receive a rod 66 which has curved spring fingers 67 at the upper end thereof projecting outwardly from a socket 68 formed at the upper end of the handle. The free ends 69 of the fingers are curved around the ball 15 and held clamped against the ball by the socket 68. The lower end of the rod 66 is threaded into a nut 70 formed integrally and axially of a cap 71. Turning of the cap in one direction will loosen 45 the fingers on the ball 16 so that the head 10 may be adjusted at the proper angle suitable for shaving. Rotation of the nut in the opposite direction will tighten the fingers on the ball and retain the head in its adjusted position.

In operation, the blade 30 is held in place between the guard 12 and forward end of the top plate 13 while the magazine 39 is filled with blades which are pressed upwardly by the spring 43 against the underface of the top plate. The free ends of the springs 26 are located above the rear edge of the blade while said rear edge abuts the shoulder 77 at the inner edge of the recess 44. The lips 32 at the front of the guard 12 prevents forward movement of the blade.

When the blade becomes dull, the button 62 (Fig. 2) is depressed releasing the top plate which is moved rearwardly carrying said blade rearwardly beneath the fingers 26 until said blade drops into the chamber 20. It must be borne in mind that the free ends of the pins 38 projecting from the underface of the plate 13 are received by the openings 37 in the blade (Fig. 9) so that when the top plate is shifted rearwardly the blade will be drawn in that direction by said pins.

The plate 13 is fully withdrawn as shown in Figure 4 and the recess 44 in the underface of said plate receives the topmost blade 30 and the pins 38 will pass into the openings 37 in said plate. The top plate is then returned to its forward posi-

tion shown in Figure 3 and the new blade is carried forwardly by the pins 38 and guided to its operative shaving position by the spring fingers 26. The free end of the latch 59 will snap into the recess 60 and lock the top plate to the body 11.

The slide 22 will be withdrawn when the chamber is filled with used blades to discharge said blades. The slide 40 is also withdrawn when the magazine has become empty for furnishing a supply of new blades.

What is claimed:

1. A magazine safety razor comprising a head provided with a pair of elongated chambers, a partition separating the chambers, said chambers being open at the top and bottom, a plate slidably mounted on the head for closing the upper open ends of the chambers, spring fingers secured at one end to the top of the partition and extending transversely across one chamber forming a repository for a stack of discarded blades, a guard at the front end of the body adjacent the repository, the forward end of the plate at the underface being provided with a recess to receive the top blade when on the guard, the free ends of the fingers being disposed at the inner end of said recess and above said recess, the other chamber forming a magazine for a stack of new blades, a spring in the magazine pressing the blades against the inner face of the plate, the blades being provided with spaced perforations, and pins projecting from the underface of the plate and received by the pins, rearward shifting of the plate causing the pins to force the top blade from the guard and the fingers to guide the top blade into the repository, said pins engaging perforations in the top blade in the magazine for carrying said blade to the guard when the plate is returned.

2. In a safety razor, an enlarged head provided with a repository for a stack of discarded blades and a magazine for a stack of new blades, a plate slidably mounted on the head and closing the top of the repository and magazine, a guard at the front end of the head adjacent the repository, said plate having a recess to receive a top blade on the guard, spring fingers secured at one end on the top of the head and extending over the repository, the free ends of fingers terminating adjacent to and above the inner edge of the top blade, the stack of new blades having spaced perforations, pins projecting downwardly from the recess and received by the perforations so that when the plate is shifted to the rear end of the head, the top blade on the guard will be forced beneath the fingers and into the repository while the pins will move into the perforations in the uppermost blade in the magazine, and means pressing the blades in the magazine upwardly against the plate, said plate, when returned, shifting the pin-engaged top blade forwardly over the fingers and into position on the guard.

3. In a safety razor, an enlarged head provided with a repository for a stack of discarded blades and a magazine for a stack of new blades, a plate slidably mounted on the head and closing the top of the repository and magazine, a guard at the front end of the head adjacent the repository, said plate having a recess to receive a top blade on the guard, spring fingers secured at one end on the top of the head and extending over the repository, the free ends of fingers terminating adjacent to and above the inner edge of the top blade, cooperating means on the top blade and plate for connecting the stack of discarded blades

releasably to the under face of the plate so that when the plate is shifted rearwardly the top blade will be forced beneath the fingers into the repository while the cooperating means on the plate and the top blade in the stack of blades in the magazine will be operatively engaged, and means pressing the blades in the magazine upwardly against the inner face of the plate, said plate, when returned, shifting the plate-engaged top blade forwardly over the fingers and onto the 10 guard.
